Primary Examiner — Jeffrey D Asch*Assistant Examiner* — Rebekah A Caruso(74) *Attorney, Agent, or Firm* — McCoy Russell LLP(57) **CLAIM**

The ornamental design for a footwear article, as shown and described.

DESCRIPTION

FIG. 1 is a left side view of a footwear article according to the present invention.

FIG. 2 is a top view of the footwear article of FIG. 1.

FIG. 3 is a right side view of the footwear article of FIG. 1.

FIG. 4 is a front view of the footwear article of FIG. 1.

FIG. 5 is a back view of the footwear article of FIG. 1; and,

FIG. 6 is a bottom view of the footwear article of FIG. 1. The broken lines in FIGS. 1-6 depict portions of the foot-

wear article that form no part of the claimed design. The oblique line shading in FIGS. 1-5 on side and front portions of the shoe represent translucent surfaces.

1 Claim, 6 Drawing Sheets(56)
